UNITED STATES PATENT OFFICE.

JOHN WALTER FLOWER, OF WIMBORNE, ENGLAND.

POWER-HAMMER.

1,380,857.

Specification of Letters Patent.

Patented Feb. 17, 1920.

Application filed August 22, 1916. Serial No. 116,381.

To all whom it may concern:

Be it known that I, JOHN WALTER FLOWER, a citizen of the United Kingdom of Great Britain and Ireland, and resident of Eclipse 5 Works, Wimborne, Dorset, England, have invented certain new and useful Improvements in Power-Hammers, of which the following is a specification, such as will enable others skilled in the art to which it applies to make and use the same.

This invention relates to hammers and while applicable for various purposes such as riveting, welding, and planishing is specially designed for riveting the end or base 15 plates of shells.

The illustrated form of the machine may be broadly described as consisting of a frame or support carrying one or more pneumatic hammers and a device preferably in 20 the form of a plunger, to assist in holding the work-piece while the hammer strikes. The work-piece is arranged on a table or carrier, usually a socket made in two parts one of which is capable of being turned 25 upon the other about an axis which, in a general way, would be about parallel to the line of stroke of the hammer, both the said parts being capable of being swung on a pivot, set at right angles to the stroke of 30 the hammer, to bring the work-piece away from or into position to be operated upon by said hammer.

The table or holder, is preferably rotated by worm gear, driven from a pulley on the 35 machine.

For the purpose of working upon shells, the construction and arrangement of the machine may be substantially as shown in the accompanying drawings in which:—

40 Figure 1 is a front elevation of a machine embodying my invention.

Fig. 2 is a side elevation of the machine shown in Fig. 1 with the shell-carrying holder or socket in operative position.

45 Figs. 3 and 4 show details of the pneumatic hammer and its cylinder.

Figs. 5 and 6 show other details.

In these drawings the machine comprises a column *a* on base *b*. This column carries 50 bracket *c* which forms the working cylinder *d*. Above this cylinder a crank *e* is fitted and has connected to it a rod *f* which forms the rod of a piston *g*.

The shaft *h* which carries the crank is fitted with fast and loose pulleys *i* and *j* on one

side and on the other side with a small pulley *k* over which a belt *l* runs.

On the lower part of the column *a* a bracket *n* carries a rotatable holder or socket made in two parts *o* and *o'*, the latter 60 of which is pivoted to the bracket at *p* and is furnished with a worm-wheel *m* adapted to be brought into and out of mesh with a worm *r* driven by a belt *l*.

The holder or socket *o* and *o'* is capable 65 of being swung by hand on its pivot *p* away from the column *a* to permit the placing in to it and the removal from it of a shell such as *z*. The bracket can be locked on the column *a* at varying heights and at any desired 70 radial position so as to suit the machine to shells, or other work-piece of varying kinds and sizes. This locking can be effected by any known or suitable means such as making the bracket of split form and clamping it 75 upon column with screws or ordinary set screws may be used.

Cylinder *d* has two side openings or vents *s* and *t* either or both of which may be controllable by any convenient means such as 80 screws.

The air piston *g* reciprocates in the upper end of the cylinder above the other piston *u* which carries the hammer *v* the nose or operative end of which projects below the extension or sleeve *d'* when striking a blow. 85 Adjacent to the nose of the hammer is the spring controlled plunger *w* which rests upon the shell and holds same while the hammer is working. In double hammer machines two pneumatic cylinders are employed with one or more devices such as the plunger *w* for holding the work-piece.

In Figs. 5 and 6 the lower end of the socket *o'* is shown pivoted at *p* and having 90 extending from it an arm *o''* below which is spindle *x'* having a flat side *x''* which engages under the said arm. This spindle is rigid with lever *x* and is movable in the bracket *n*. When the lever *x* is moved it 100 turns the spindle *x'* and alters the tilt of the arm *o''* thereby moving the top of the shell *z* in relation to the hammer *v*. By this means the blows from the hammer are made in concentric circles on the shell. The necessary 105 movement of the shell is very little and is insufficient to disengage the worm *r* from the worm wheel *g* the said worm and the teeth of the said worm wheel being sufficiently deep to engage each other in any 110

position which the shell may take to be hammered.

When the shell has taken any desired position under the hammer the lever y is pulled 5 so as to cause a collar y' which has a sloping face to press against a collar n' on the bracket n , said collar n' also having a sloping face, and cause the sides of the bracket about the pivot p to grip the lower part of the socket member o' and hold it in the required position.

When the machine is started the hammer strikes rapid blows as the shell revolves. After the first revolution or a sufficient number of revolutions of the shell the lever y is moved and releases the part o' of the socket, the lever x is then employed to shift the holder and with it the shell and the grip on the bracket is re-assumed by moving back 20 the lever y so that the blows from the hammer fall in a smaller circle and complete the joint.

It will be seen that the machine is complete in itself, no air compressor or pipe lines are required and thus trouble from rust and 25 particles of rubber from the pipes and hose are

eliminated as well as risks of compressor and pipe line explosions, caused by accumulations of carbonized oil. In addition to these advantages a variable elastic blow free 30 from all jar is obtained.

What I claim and desire to secure by Letters Patent is:—

In combination, a standard, a hammer carried thereon, a crank shaft, a rod connecting the crank shaft to the hammer, a bracket on said standard, a rotatable holder for carrying a workpiece and mounted to be swung about a pivot set out of alinement with the stroke of the hammer, a worm wheel 35 secured to the holder, a worm shaft with worm gearing with the said wheel, driving means from the crank shaft to the worm shaft and means for swinging the holder about the pivot.

In witness whereof I have hereunto set my hand in presence of two witnesses.

JOHN WALTER FLOWER.

Witnesses:

LILY PARRY,
HENRY FAIRBROTHER.
